UNITED STATES PATENT OFFICE.

ANTON MALLY, OF CHICAGO, ILLINOIS.

BED.

1,203,379.

Specification of Letters Patent. Patented Oct. 31, 1916.

Application filed October 23, 1915. Serial No. 57,445.

To all whom it may concern.

Be it known that I, ANTON MALLY, a subject of the Emperor of Austria-Hungary, who have declared my intention of becoming a citizen of the United States, and a resident of the city of Chicago, county of Cook, and State of Illinois, have invented certain new and useful Improvements in Beds, of which the following is a specification.

My invention relates to beds, and more specifically to a bed designed for use especially for invalids.

The object of my invention is the production of a bed of the character mentioned which will be of durable and economical construction and one which will afford great ease and comfort to the occupant of the bed.

Other objects will appear hereinafter.

The invention consists in the combinations and arrangements of parts hereinafter described and claimed.

The invention will be best understood by reference to the accompanying drawings forming a part of this specification, and in which,

Figure 1 is a rear elevation of a bed embodying the invention, portions of the construction being broken away to expose underlying parts, and the upper end portion of the movable panel of the construction being omitted, Fig. 2 is a vertical longitudinal section through the head portion of the bed in the condition shown in Fig. 1, that is with the auxiliary bed parts in operative position, Fig. 3 is a view similar to Fig. 2 showing the auxiliary bed parts in folded or inoperative position, Fig. 4 is an enlarged detail section taken on line 4—4 of Fig. 6, Fig. 5 is a detail section taken on line 5—5 of Fig. 4, Fig. 6 is a horizontal section of the construction, as shown in Fig. 1, Figs. 7 and 8 are enlarged detail sections taken on lines 7—7 and 8—8 respectively of Fig. 6, and Fig. 9 is a horizontal section through a back rest of slightly modified form.

The preferred form of construction, as illustrated in the drawings, comprises a bed the portion of which forward of the head piece 11 thereof being of conventional construction. Said head piece 11 is formed with a central opening 12 which is adapted to be closed by a vertically movable panel 13 the lateral edges of which slidably engage in guide channels 14 formed in said head piece, as clearly shown in the several

views. Coöoperating with the panel 13 are counterbalance weights 15 mounted for free vertical movement in two of the vertical hollow bars of said head piece, said counterbalance weights being connected with the lower ends of cords 16 which pass upwardly over channel pulleys 17 and are connected at their upper ends with the lower end of panel 13, as clearly shown in Fig. 1. The construction is such that said counterbalance weights are adapted to yieldingly hold said panel at its upper terminal of movement permitting, however, of lowering of the same to close said opening 12, as shown in Fig. 70. The pulleys 17 are inclosed in housings 18 and the counterbalance weights 15 are provided at their opposite ends with disks 19 of leather or other suitable material which serve as buffers to prevent rattling of 75 said counterbalance weights during vertical movement thereof, as will be readily understood.

Arranged at the rearward side of the head piece 11, at the lower end thereof, are vertically extending posts or supports 20, said posts being mounted for vertical adjustment in guide straps 21 and 22, the former of which are secured to the lower horizontal bar of said head piece, and the latter of which are mounted upon supporting straps 23 which arise from said cross piece, as clearly shown in Figs. 1 and 2. Set screws 24 coöperate with the guide straps 21 and 22 to lock the members 20 in positions 90 of vertical adjustment. Also coöoperating with members 20 are pins 25 adapted for engagement with spaced slots provided in said posts, the pins 25 being adapted for contact with the upper sides of straps 22 in 95 order to serve as further means of holding said posts in positions of vertical adjustment.

Rockingly mounted in the upper ends of posts 20 is a transversely extending bar 27 to which are secured the rearward ends of angular arms 28. Pivotedly connected at 29 with the forward ends of arms 28 is a back rest consisting of side bars 30 and transversely extending bars 31 connecting bars 105 30. Connecting the bars 30 are also interwoven metallic straps 32 the lateral ends of which are connected by means of helical tension springs 33 with the bars 30. A resilient frame or backing is thus formed 110 against which a cushion 34 is adapted to rest. The connecting bars 31 are offset rear-

wardly at their central portions in order to permit of depression of the back rest when in use, as will be readily understood.

If a more economical construction is desired, the metallic straps 32 may be dispensed with and in lieu thereof a piece of fabric 32' employed, as clearly shown in Fig. 9. Where this construction is used the cushion 34 may also be dispensed with, but 10 in this event straps 32" of fabric will be employed at the lateral edges of the member 32' in order to cover the springs 33. The back rest which is thus formed is so connected with the arms 28 as to permit of 15 angular adjustment of said back rest to any position desired, in order to suit the convenience of the occupant of the bed, said back rest being held in positions of angular adjustment by means of a substantially 20 U-shaped supporting member 35 which is adapted for engagement with spaced slots 36 formed in the upper edges of arms 38. To facilitate ready disengagement of the rearward or free end of the member 35 from 25 the slots 36, a cord 37 is provided which is connected at one end with one side of the member 35, as shown in Fig. 1, said cord projecting upwardly over a channel pulley 38 to the front side of the back rest where 30 the same may be readily engaged by the occupant of the bed. At the opposite edge of the back rest is provided a depending cord 39 which is adapted for use in facilitating angularly adjusting the back rest to 35 the position desired by the occupant of the bed.

The lower end of the back rest rests upon the upper side of the mattress or clothing of the bed and in order to permit of ready 40 movement of the back rest relative to the mattress or bed clothing engaged, the lower ends of bars 30 are provided with rollers 40. The back rest, when in use, projects through the opening 12 in the head piece 45 of the bed, and when not in use, is adapted to be rocked rearwardly through said opening to a position behind said head piece. Said back rest is held in inoperative position by engagement of the rearward ends of arms 50 28 with a transversely extending bar 41 supported by rearward projections on posts 20, as clearly shown in Figs. 2, 3, 4 and 5. The bar 41 is so positioned relative to the pivotal axis of said back rest that, when the latter 55 is in its rearward position, the same will be beyond the dead center and therefore will remain in this position by gravity. Also, the connection of the back rest proper with the supporting arms 28 is such, that the 60 upper end of said back rest is positioned forwardly of the pivotal points 29, when the back rest is in inoperative position, and whereby said back rest proper will by gravity assume the position shown in Fig. 3.

Coöperating with the bed is also a sup-

porting element or table consisting of arms 42 rigidly connected at their rearward ends by a cross bar 42', said arms having laterally projecting trunnions 43 at their rearward ends which pivotally engage with slots 70 44 formed in the posts 20. Forward rocking of the arms 42 is limited by means of stops 45 which are adapted to engage against the upper ends of posts 20, the arrangement being such that when the stops 45 are in engagement with said posts, the forward ends 75 of arms 42 will be substantially horizontally disposed.

Carried at the forward or free ends of arms 42 is a table consisting of leaves 46 80 and 46', the leaf 46 being fixed to end pieces 47, and the leaf 46' being hingedly connected with said leaf 46 so as to permit of said leaf 46' being swung to the position shown in full lines in Fig. 3 and dotted 85 lines in Fig. 7. The end pieces 47 are adjustably connected with the arms 42 by means of outwardly projecting pins 48 anchored in said end pieces 47, the outer ends of said pins projecting through elongated 90 slots 49 formed in the arms 42. Hand wheels 50 are threaded upon the outer ends of pins 48 in order to effect clamping of the end pieces 47 in positions of pivotal adjustment. Rollers 51 are provided upon the 95 pins 48 for engagement with the longitudinal edges of slots 49 so as to alleviate friction in the shifting of the table top relative to supporting arms 42. The table thus formed is conveniently positioned for the 100 occupant of the bed and affords considerable convenience in eating or where it is desired to support articles in front of the occupant. The leaf 46' is provided with pivoted fingers 52 adapted to be swung upwardly to the position shown in Fig. 7 in order to constitute a rest for books, as will be readily understood. The upper side of leaf 46' is provided with recesses 53 in order to accommodate the fingers 42 when 110 the latter are not in use. The pivotal adjustment which is afforded the end members 47 is of course of advantage in the use of the device as a book rest since it affords adjustment of the book to any angle desired. 115

The leaf 46' is held in folded position by means of a spring detent 54 and the table top is locked against vertical tilting by means of a laterally projecting finger 55 provided at the front end of one of the end 120 pieces 47 which is adapted for engagement in a recess 56 provided in the corresponding end of the adjacent supporting member 42, as clearly shown in Figs. 6 and 7. The slots 49 of course permit of the desired shifting of 125 the table top in order to effect engagement or disengagement of the finger 55 with or from the recess 56. The supporting arms 42 are depressed at the central portions thereof as at 57 in order to accommodate the arms or 130

elbows of the occupant of the bed so as to further add to the convenience and comfort of the occupant.

When the table is in use, the arms 42 project from the opening 12, as seen, the arrangement being such that when the table is not in use, the same may be rocked upwardly through said opening to position behind the head piece 11. Said table element is supported in operative position by engagement of the rearward ends of arms 42 with stop blocks 58 adjustably secured to the posts 20 by means of coöperating bolts and nuts 59, as clearly shown in Figs. 4 and 5. In order to afford the desired vertical adjustment of the blocks 58, the same are vertically slotted. An elongated washer 60 coöperates with each block for engagement with the head of the corresponding bolt 59 and the shoulder of the corresponding bar 41, as shown in Fig. 5. The arrangement of said stop blocks 58 also is such that when the arms 42 are in engagement therewith, said arms will be positioned beyond the dead center and so will be held by gravity in inoperative or folded position. In the folding or swinging of the back rest or table elements, each is independent of the other, permitting of the use of either or both, as may be desired. When neither is in use, the panel 13 is slid downwardly to close the opening 12, in which event the bed is to all intents and purposes the same as the conventional bed.

While I have illustrated and described the preferred forms of construction for carrying my invention into effect, these are capable of variation and modification without departing from the spirit of the invention. I, therefore, do not wish to be limited to the

precise details of construction set forth, but desire to avail myself of such variations and modifications as come within the scope of the appended claims.

Having described my invention what I claim as new and desire to secure by Letters Patent is:

1. In a device of the class described, the combination of a bed comprising a frame having a head piece, said head piece having an opening; a supporting element mounted on said frame for vertical adjustment; an auxiliary bed member pivotally mounted upon said supporting element so as to permit of movement thereof through said opening to and from operative position; and a removable panel for closing said opening, substantially as described.

2. In a device of the class described, the combination of a bed comprising a frame having a head piece; a pair of vertically adjustable supports mounted on said frame adjacent said head piece; means for locking said supports in positions of vertical adjustment; an auxiliary bed member pivotally mounted upon said supports so as to permit of swinging of said member to and from position over said bed; and vertically adjustable blocks on said supports for limiting swinging of said member in one direction, substantially as described.

In testimony whereof I have signed my name to this specification on the presence of two subscribing witnesses.

ANTON MALLY.
